US00D740079S

(12) **United States Design Patent**
Miksovsky et al.

(10) **Patent No.:** **US D740,079 S**
(45) **Date of Patent:** **** Oct. 6, 2015**

(54) **FORK**

- (71) Applicant: **humangear, Inc.**, San Francisco, CA (US)
- (72) Inventors: **Christopher A. Miksovsky**, San Francisco, CA (US); **Clint N. Slone**, San Francisco, CA (US); **Evelyne Chaubert**, San Francisco, CA (US); **Charlie Nghiem**, Oakland, CA (US)
- (73) Assignee: **humangear, Inc.**, San Francisco, CA (US)
- (**) Term: **14 Years**
- (21) Appl. No.: **29/510,006**
- (22) Filed: **Nov. 24, 2014**

(57) **CLAIM**

We claim the ornamental design for a fork, substantially as shown and described.

DESCRIPTION

FIG. 1 is a top perspective view of the fork.

FIG. 2 is a bottom perspective view of the fork.

FIG. 3 is a top plan view of the fork.

FIG. 4 is a bottom plan view of the fork.

FIG. 5 is a right side elevational view of the fork.

FIG. 6 is a left side elevational view of the fork.

FIG. 7 is an enlarged handle end elevational view of the fork; and,

FIG. 8 is an enlarged head end elevational view of the fork. The broken lines are shown for illustrative purposes only and form no part of the claimed design.

1 Claim, 8 Drawing Sheets
